UNITED STATES PATENT OFFICE.

NEWTON K. BOWMAN, OF NORTH LAWRENCE, AND JOHN C. HEWITT, OF CANTON, OHIO,
ASSIGNORS, BY DIRECT AND MESNE ASSIGNMENTS, TO THE AMERICAN HOOP
SPLICE COMPANY, OF CANTON, OHIO, A CORPORATION OF DELAWARE.

HOOP FORMING AND SPLICING MACHINE.

1,122,680.

Specification of Letters Patent.

Patented Dec. 29, 1914.

Application filed October 25, 1912. Serial No. 727,758.

To all whom it may concern:

Be it known that we, NEWTON K. BOWMAN and JOHN C. HEWITT, citizens of the United States, residing at North Lawrence and Canton, respectively, in the county of Stark and State of Ohio, have invented certain new and useful Improvements in Hoop Forming and Splicing Machines, of which the following is a specification.

10 Our invention relates to machines designed for bending hoop blanks into circular form and splicing the ends of the hoop blanks, and particularly to improvements on the hoop forming mechanism shown in

15 the prior patent granted to Newton K. Bowman on the 31st day of July, 1908, No. 827,607.

The general object of the invention is to provide a machine into which hoop blanks 20 may be inserted, and by which the blank may be bent around a form, and to provide in connection therewith means whereby splice plates having prongs projecting therefrom may be fed from a magazine, forced 25 against the meeting ends of the hoops and clamped securely thereon, the completed hoop being then ejected from the machine.

A further object is to improve the detailed construction of the machine illustrated in the prior patent above referred to so as to provide for a simpler and more positive actuation of the mechanism therein shown and generally to simplify the construction illustrated.

35 A further object is to provide a form around which the hoop blank is bent, which form is adjustable within certain limits so as to accommodate blanks of different sizes.

A further object is to provide means for 40 positively engaging the bent blank by the bending means so as to prevent any shifting of the free ends of the blank when the splice plate is being applied.

A still further object is to provide improved mechanism for feeding the splice plates one by one from the magazine, and means coacting therewith for preventing the ejection of more than one splice plate at a time from the magazine.

50 A further object is to provide mechanism for stopping the ejection of blanks from the magazine as in case of breakage of any part.

Another object is to provide means for supporting hoop blanks in such position

that they may be readily fed to the magazine. 55

Our invention is illustrated in the accompanying drawings wherein:

Figure 1 is a perspective view of a hoop forming and splicing machine constructed 60 in accordance with my invention. Fig. 2 is a side elevation of the machine shown in Fig. 1. Fig. 3 is a side elevation taken from a viewpoint opposed to that in Fig. 2. Fig. 4 is a plan view of the machine. Fig. 5 is 65 a longitudinal section on the line 5—5 of Fig. 4. Fig. 6 is an enlarged fragmentary plan view of the blank clamping mechanism, the form and a portion of the blank bending jaws, the blank bending jaws being 70 in their retracted position. Fig. 7 is a like view to Fig. 6 but showing the jaws in their forward position and the hoop bent around the form. Fig. 8 is an enlarged sectional view of the splice plate magazine and the 75 means for feeding a splice plate therefrom. Fig. 9 is a like view to Fig. 8 but showing the parts in the position taken when the splice plate is bent around and clamped to the free ends of the hoop. Fig. 10 is a like 80 view to Fig. 9 but showing the jaws partly opened and the hammer projected to complete the operation of clamping the splice plate upon the hoop. Fig. 11 is a longitudinal sectional view on the line 11—11 of 85 Fig. 9. Fig. 12 is a perspective detail view of the base plate carrying the hammer, the hammer mounted thereon and the ejector. Fig. 13 is an under side perspective view of the plate 14 shown in Fig. 12 and showing 90 the clamping slide, the figure also showing in perspective the levers whereby the clamping slide is operated and the ejector actuated. Fig. 14 is a perspective detail view of the uppermost clenching jaw. Fig. 15 is a 95 perspective view of the forward end of the magazine. Fig. 16 is a vertical section on the line 16—16 of Fig. 17. Fig. 17 is a vertical section on the line 17—17 of Fig. 16. Fig. 18 is a perspective detail view of the 100 gate and the yoke upon which it is mounted. Fig. 19 is a fragmentary elevation partly sectional of the end of one of the arms 20, the lower roller engaging the track 8 and the upper roller which engages the hoop being in section. Fig. 20 is a perspective detail view of the meeting ends of a hoop and a perspective view of the splice plate before 105

its application to the hoop. Fig. 21 is a like view to Fig. 20 but showing the splice plate which has been applied and clenched.

Corresponding and like parts are referred to in the following description and indicated in all the views of the accompanying drawings by the same reference characters.

The framework of the machine comprises the parallel, spaced, longitudinally extending supporting beams 2 which may be formed in any suitable manner but as shown are castings provided with the legs 3. These side pieces 2 are supported in spaced relation to each other in any suitable manner.

Mounted upon the middle of the supporting beams is a form composed of approximately semi-annular segments constituting opposed sections 5 and 6, each having an inner vertical flange 7 and a basal flange 8 formed with a marginal flange 9, the marginal flange 9 being less in height than the flange 7. This marginal flange 9 is concentric for a distance with the flange 7. The basal flange of each section is extended rearward and inward as at 10 at a tangent to the curve of the flanges 7 and 8, and these flanges 7 and 8 of each section are also extended rearward on each side of the web 10 as at 7^a and 9^a. The basal flange and its extension 10, together with the flanges 7 and 9 constitute opposite tracks extending forward in divergent lines from the rear of the machine and then curving in an arcuate form forward and toward the middle of the machine. The inner vertical flange 7 of each section is extended rearward and toward the middle of the machine and the extension 7^a of said flange is of less height than the flange 7. It will be seen that the two sections 5 and 6 when in position constitute an annular form interrupted at front and rear. The sections constituting the form above described are attached to a base plate 14 as will be later described. In order to provide for the adjustment of this form to suit larger or smaller hoops, we form the rear ends of the segmental webs of the form each with a slot 13 and the forward ends each with a bolt opening. The sections 5 and 6 are mounted upon the plate 14 (see Fig. 13) which is provided with upwardly projecting bolts 15 which pass through the forwardly disposed perforations in the sections and upwardly projecting stud bolts 16 which pass through the arcuate shaped slots 13. Thus the segments are pivoted each at its forward end and adjustable nearer to or farther from each other at their rear ends.

The rear portions of the side pieces 2 as shown in Fig. 5 are relatively near together and adjacent their upper edges are formed with longitudinally extending 65 grooves 17 upon which moves a slide or

carriage 18 having lateral tongues projecting into the grooves. Extending up therefrom are studs 19 upon which are pivoted the bending arms or formers 20. Each of these arms as shown in Fig. 7 is bowed or 70 curved and each has a strengthening flange 21 on its inner edge, this flange forming the inner face of each arm and having a width substantially equal to the width of the hoop upon which the arm is to act. 75 At its rear end each arm is formed with a collar 22 through which the corresponding pivot stud projects. Mounted upon the forward end of each arm is a roller 23 which extends down below the arm and which 80 engages with and is guided by the corresponding track formed by the flanges 7, 9, 7^a and 9^a.

It will be seen that upon a forward movement of the carriage from the position 85 shown in Fig. 6 to that in Fig. 7, the forward ends of the arms will first move in straight divergent lines and then will be moved toward each other, and that upon a reverse movement of the slide this motion 90 will be reversed so that the arms are first drawn apart and then move in straight lines toward the center and rear of the machine into the position shown in Fig. 6.

In order to reciprocate the slide it is 95 formed with a depending yoke 24 having a transverse pin 25 with which the slotted upper end of a lever 26 engages as illustrated in Fig. 5. This lever is pivotally mounted at its lower end between the rear 100 pair of legs and is provided with a laterally projecting stud engaging a cam, this cam acting to oscillate the lever and thereby reciprocate the slide. The details of the driving mechanism will be described later, 105 however.

Mounted at the rear end of the machine and extending between the spaced side pieces 2 is a cross piece 27 having a central hub through which passes a stem 28 having a head 29 at its inner end constituting a buffer, a coil spring 30 being disposed around the stem 28 and between the head and the cross piece and resisting any inward movement of the head. This buffer takes 110 up the shock caused by the complete retraction of the sliding carriage on which the arms are mounted. This buffer is illustrated most clearly in Figs. 4 and 5.

Mounted upon the plate 14 as illustrated 115 in Fig. 13 is a blank clamping jaw designated 31 which is adapted to reciprocate toward and from the rear portion of the form. As illustrated, the under side of the plate 14 is formed with guides 32 between 120 which is mounted a slide 33 to the upper face of which the jaw 31 is attached. This jaw 31 is curved concentrically to the flanges 7 and is adapted to be moved up into parallel relation to said flanges, the slide 33 recip- 125

roating for this purpose. This slide is reciprocated by means of a bell crank lever engaging a cam as illustrated in Fig. 5 and as will be further described.

5 In order that the hoop may be held firmly in place after it has been bent around the form, we provide each of the sections 5 and 6 of the form with a prong 34 (see Fig. 6) disposed each at the forward end of its cor-

10 responding flange 7, which prongs engage the hoop as its ends are forced inward against the form. We may also provide the arms 20 with springs 35 adapted to engage the hoop as the arms embrace the form 15 which firmly hold the hoop in place with a resilient grasp. After the hoop has been bent around the form by the bending arms 20 and the ends abut against each other, it is in position for the splice plate.

20 As shown in Fig. 20, the splice plate *b* consists of a thin metal plate having prongs punched from it. These prongs are arranged in two vertical sets, one set being spaced from the other so as to leave an intermediate plain portion *b'* and the machine is designed to bend or fold the plate around abutting ends of the hoop as shown in Fig. 21. The splice plates are initially carried in an elongated magazine 36 which as shown 25 30 in Figs. 4 and 5 is mounted on supporting brackets disposed on cross members 37 supported on the side beams 2. Each magazine consists of an elongated trough having a width equal to the width of the splice plate 35 but less in height.

The splice plates are fed forward in the trough by a follower 38 (see Fig. 8) which is attached to a cord 39 extending forward along the bottom of the magazine and passing 40 over a roller 40. The cord is then carried back to the end of the machine and passes over a pulley 41 supported on a bracket 42. A counterweight 43 (see Fig. 3) is attached to the depending end of the cord 45 and acts to feed the follower forward. In order that the follower may be held steady within the magazine, it is provided with an extension 45 and a block 46, which block fits the internal configuration of the magazine. 50 To accommodate the cord 39, the bottom of the magazine is longitudinally grooved as at 44.

Adjacent the forward end of the magazine in the bottom thereof is a transverse 55 delivery slot through which the splice plates are adapted to be fed one by one in succession, and disposed in the magazine trough adjacent this slot and normally inward thereof is a detent or gate 48 (Fig. 17) having a protuberant middle portion 49. The purpose of this protuberant middle portion 60 is to engage the middle portion of the splice plate so that the face of the gate will not come in contact with the sharp ends of the 65 prongs on the splice plate and tend to bend

these prongs inward. The gate is attached to a yoke 50 with ribs 51 on its sides which travel in slots 52 formed in the forward end of the magazine as shown in Fig. 15. The rearward extremities of the ribs 51 are provided with the outwardly projecting lugs 53, each lug being formed with an inclined face 54 adapted to be engaged by actuating wedges as will be later described.

Extending vertically downward at the 75 forward ends of the sides of the magazine and extending across the slots 52 are the blocks 55 and disposed between each of the blocks 55 and the adjacent lug 53 is a coil spring 56 which acts to urge the gate rearward with relation to the forward end of the magazine and normally hold the gate in such position that it will prevent the discharge of a splice plate from the discharge opening 47. This position is shown in Fig. 80 9. When the gate is moved toward the forward end of the magazine, it permits the forward movement of the first splice plate and permits it to drop through the slot and be received upon the clamping devices as 90 will be later described.

As a means of actuating the gate and reciprocating it toward and from the front of the magazine, we provide on each side of the magazine at its forward end the 95 vertically disposed rods 57 (see Fig. 15). These rods pass through guide blocks 58 attached to the sides of the magazine and the upper and lower ends of the rods are connected by the cross bars 59 and 60 respectively. Springs 61 surround the rods 57 at the upper ends thereof and disposed between the upper cross bar 59 and the blocks 58 and tend to force the rods 57 upward.

Mounted upon each rod 57 is a member 62 105 having the form of a block and provided with an upwardly and forwardly extending rounded portion 63 which acts as a wedge and which is adapted to engage with the forward inclined face of the corresponding 110 lug 53. It will be seen that as the rods 57 move downward, the gate will be moved toward the front end of the magazine to permit the discharge of a splice plate and that as the rods move upward, the springs 115 56 will force the gate forward into a position to prevent the discharge of the splice plate. Means is also provided for manually preventing the discharge of a plate, but this mechanism will be later described.

Means must be provided for positively forcing the first splice plate of the series contained in the magazine forward into position where it may drop through the slot 47, and also to prevent or detain the succeeding splice plates from being moved forward at the time that the first splice plate is dropping. For this purpose we provide a chisel or wedge shaped separating blade designated 64 which is mounted upon the cross 120 125 130

bar 59 as shown in Fig. 15 and which has a downwardly tapered blade formed with a chisel edge as illustrated in Fig. 18. As the bar 59 is drawn downward by the rods 57, this blade will enter between the rear face of the first splice plate and the front face of the next succeeding splice plate and will support these splice plates forcing the first splice plate forward into register with the slot 47 and holding the succeeding splice plates back. The means for reciprocating the bars 57 is illustrated in Fig. 8 in which 65 designates a bell crank lever pivotally mounted upon the under side of the magazine trough, the forward end of this lever extending over and engaging with the cross bar 60. The other end of the bell crank lever is provided with a roller 66 which is operated by means of operating mechanism to be later described. After the splice plate has been discharged from the magazine, it drops downward upon suitable supporting means and is carried forward and pressed against the abutting ends of the hoop by 25 means of a movable abutment. After it is so pressed into engagement with the hoop, the bending means operate to bend the upper and lower ends of the splice plate around the hoop and then a hammer operates which forces the splice plate home and forces the prongs firmly into the wood of the hoop.

The mechanism for receiving the splice plate after it is discharged, for carrying it forward against the hoop and bending it, will now be described. Brackets 37 as before stated are supported on cross pieces 47 which are rectangular in form so as to provide guides through which operates a plunger bar 67 (see Figs. 8, 9 and 10). This bar is formed at its forward end with a head 68 having a horizontally extending concave recess 69 in its forward end, this recess having the contour of the front face of the 45 hoop and its top edge. The mechanism for reciprocating this bar will be later stated. The bar 67 is formed with guide channels 70 in its opposed sides in each of which is mounted a slide 71, each slide being shorter 50 than the length of the corresponding channel. The bar is transversely slotted as at 72 and 72^a for bolts which pass through these slides and through the bar. The head 68 is reduced in thickness and pivotally 55 mounted thereon are the opposed jaws 73, one above and one below the head. To provide this pivotal mounting, the head is formed with knuckles and each jaw has a pair of ears which embrace the knuckles and 60 through which passes a bolt 74. The jaws project in front of the head and each jaw is provided with an inwardly extending terminal end or lip 75. Each jaw is also preferably formed with a medially disposed 65 strengthening rib and each jaw extends

rearward to a point approximately in line with the forward end of the slot 72. Links 76 extend from the rear end of each jaw, there being a pair of links to each jaw embracing the bar 67, and the upper and lower 70 pairs of links are connected by means of a transverse pivot bolt which passes through the slot 72 and operates therein. This pivot bolt also passes through the slides 71 so that as the slide is reciprocated, the jaws 75 will be opened or closed.

Mounted on the under side of the bar 67 rearward of the slot 71^a is a downwardly extending bracket 77 which is formed with spaced ears at its lower end between which 80 operates a bell crank lever designated 78, one arm of which extends forward and is provided at its end with a laterally projecting cam engaging roller 78^a. The other arm of the bell crank lever projects upward 85 on both sides of the bar 67, it being provided with parallel ears for this purpose, and through the arm formed by these parallel ears passes a bolt 80 which also passes through the rear ends of the slides 71. It 90 will therefore be seen that an oscillation of the lever 78 will cause a reciprocation of the slides 71, a reciprocation of the pivot pin 76 and an oscillation of the jaws 73, and that because of the fact that the bar 67 is 95 slotted, these movements will occur independently to a certain extent of the movement of the bar 67.

Means must be provided for supporting a splice plate when it is discharged from 100 the magazine and guiding it into position immediately in front of the jaws 73. To this end as illustrated in Fig. 14, the upper jaw has attached to it upwardly extending guides designated 79. These guides are U-shaped in cross section disposed at each end of the jaw and are spaced from each other the width of a splice plate. As illustrated, these guides are carried upon the face of the upper jaw 73 by means of a transverse 110 angle iron which is bolted to the upper face of the jaw adjacent its forward face when the jaw is in the position shown in Fig. 8. The guides 79 extend directly upward and are disposed immediately beneath the discharge opening 47 of the magazine so that a splice plate dropping from said opening will enter said guides and be guided down to the position shown in Fig. 8. In order to hold it in this position and prevent its 120 immediate descent to the position shown in dotted lines in Fig. 8, we provide a downwardly extending supporting hook 81 illustrated most clearly in Fig. 8 which at its upper end is attached to the magazine and 125 has a lower end bent at right angles as at 82 and which when the parts are in the position shown in Fig. 8 extends through a perforation 83 in the plate 80 so that it projects beyond the face of the jaw and beyond 130

the face of the plate in such position as to support the splice plate as shown in full lines in Fig. 8. It will be seen from Fig. 9, however, that when the plunger bar 67 moves forward, the terminal end 82 of the hook 81 will be withdrawn from the perforation, permitting the splice plate to drop down into the position shown in dotted lines in Fig. 8 where it is supported by means of a hook shaped lug 84 projecting outward from the face of the lower jaw. In this position the splice plate is supported in advance of both jaws and in such position that its middle is in alinement with the middle of the hoop. After this has been accomplished, the bar 67 is moved forward, that is, toward the hoop carrying the splice plate with it, and the splice plate is forced against the face of the hoop. The jaws are sufficiently open at this time to permit the passage of the hoop between the jaws and the head 68 therefore forces the splice plate to conform to the contour of the face of the head thereof as shown in Fig. 10. Previous to this, however, a hammer or anvil 85 has been moved forward into position behind the meeting ends of the hoop so as to form a solid abutment for the hoop and thus cause the prongs of the splice plate to be forcibly pressed into the wood of the hoop.

The forward movement of the head 68 causes an initial bend of the splice plate so that the ends of the splice plate may be engaged by the terminal ends 75 of the jaws 73 as the jaws are moved from the position shown in Fig. 8 to that shown in Fig. 9. At this time the hammer is retracted so as to permit the jaws to close, but as soon as the jaws are opened, as in Fig. 10, the hammer is again forced between the jaws to deliver a final blow upon the splice plate.

The hammer is designated as 85 and is mounted in a guide 86. The hammer is actuated by means of an angular lever 87 mounted loosely upon the shaft 115. This lever has a slotted upper end which passes into a slot in the hammer. The free end of the lever is made in two sections, the section 88 being pivoted to the free end of the lever for rotary adjustment, and formed with a slot 90 through which a bolt carried by the body of the lever passes, whereby to lock the section 88 in any adjusted position. The outer end of the section 88 is formed with an outwardly projecting roller 88a adapted to engage in a cam track 118 as will be later described.

For the purpose of ejecting the barrel hoop after it has been spliced, we mount upon the plate 14 between the segments 5 and 6 an ejecting finger designated 91 which is pivoted at its middle between ears 92 and which is bifurcated at its rear end

for engagement with a depending link 93 as illustrated in Fig. 5, which in turn is connected to an operating lever. The rear end of the finger 91 is widened so as to engage under the rear portion of the barrel hoop, 70 the finger being disposed so that its rear end projects into the space between the rear ends of the sections 5 and 6 as illustrated in Fig. 4, and therefore immediately beneath the hoop when the same is closed. As soon 75 as the ends of the hoop have been fastened and the hammer and plunger bar retracted so that the hoop is free, then the rear end of the finger is snapped upward lifting the hoop into such position that it 80 may be readily grasped by the hands of the operator and removed.

The mechanism for operating the several instrumentalities heretofore described is as follows: The driving shaft by which power 85 is communicated to the machine is designated 94. This shaft passes entirely through the frame upon which the machine is supported and carries upon it the usual driving pulley 95 and the clutch mechanism 90 96, the power being communicated to the machine or removed from engagement therewith by means of the shipper lever 97. The shaft 94 is provided with a pinion 98 which engages with a toothed gear wheel 95 99 mounted upon a shaft 100. This shaft passes entirely through the frame of the machine and carries on its extremity the pinion 101 (see Fig. 2). Mounted loosely upon the shaft 94 is a toothed wheel 102 100 constituting an idler and large in size relatively to the pinion 101. This gear wheel 102 meshes with a toothed gear wheel 103 mounted upon a shaft 104 which extends through the rear end of the machine and carries upon it opposed cam disks 105. There are two of these disks, each having cam tracks upon its inner face so as to form a double cam, as it may be termed, for the actuation of the plunger bar 67. This bar 110 at its extremity is formed with laterally projecting pins 106 upon which are mounted the rotatable sleeves 107. The inner face of each cam disk is formed with a cam track 108 which is set eccentrically to the axis of 115 rotation of the cam disk, and it follows from this that a rotation of the shaft 104 will cause a reciprocation of the plunger bar 67. The reason for having the opposed cam disks is that thereby a much firmer engagement is secured and the stroke is more positive with less chance of any of the parts bending or giving than would be the case were only one cam used.

Referring to Figs. 2 and 5, it will be seen 125 that passing through the side pieces 2 of the main frame is a shaft 109 which at its outer end is provided with a gear wheel 110 which meshes with the pinion 101. This shaft 109 carries upon it the cam 111. This 130

cam has a portion of its cam track extending circumferentially around the disk, the remainder of the cam track extending in an approximately chordal line across the face 5 of the disk as at 112, the middle of this transversely extending portion being deflected toward the center of rotation as illustrated in Fig. 10. Projecting into this cam track is the roller 78^a. It will be seen from 10 Fig. 5 that so long as the roller 78^a engages with the circumferential portion of the cam track, the slides will be held in their retracted position but that as this roller engages with the transverse portion of the cam 15 track 112, the free end of the lever 78 will be depressed as it enters the chordal portion of the cam track, thus moving the slides forward, spreading the links 76 and separating the rearward extensions of the jaws 20 78 and causing the jaws to grip around the hoop and splice plate as shown in Fig. 9. The depressed middle portion of the cam track 112 causes the final gripping of the jaws which locks the splice plate upon the 25 hoop and as this middle portion passes, the jaws again rise to the position shown in Fig. 10 to permit the entrance of the hammer between the jaws. Meshing with the gear wheel 110 is a gear wheel 113 which is relatively large in proportion to wheel 110 and is mounted upon a shaft 114. Mounted upon a shaft 115 is a gear wheel 116 which meshes with gear wheel 113 and which forms the axis of the angular lever 87 above 30 35 referred to. Mounted on the shaft 114 is a cam 117 formed as illustrated in Fig. 5 upon one face with a cam track 118. This cam track is concentric to the axis of the cam for a portion of its length, but has an offset portion 119. The circular portion of the cam track tends to hold lever 87 in such position that the hammer is held normally against the meeting ends of the hoop, but when the roller on the lever meets the beginning of the offset portion 119 the lever 40 will be shifted to quickly withdraw the hammer to permit the ends of the splice plate to be clamped around the hoop and then the hammer will be forced forward to 45 its normal position delivering the final blow upon the splice plate, as above stated.

The gear wheel 116 meshes with an idler pinion 120 which meshes again with an idler pinion 121, both of these pinions 55 being mounted upon stub shafts projecting from the side frame of the machine. The idler pinion 121 in turn meshes with a relatively large gear wheel 122 mounted upon a shaft 123 which is supported in bearings 60 carried by the side members 2 of the frame. This shaft 123 extends transversely across the frame, and as seen in Fig. 5 carries the cam disk 124 which is circular for nearly its entire extent but has projecting from it

the stud 125 having bevel faces. This stud 65 is adapted to engage with the rear end of a lever 126 which carries at its end a roller 127 tracking upon the periphery of the cam disk 124. This lever is rotatably mounted at its middle on a shaft 128 (see Fig. 13), 70 and the forward end of the lever is connected to the link 93. It will be obvious then that the lever 126 will be reciprocated, once in each rotation of the shaft 123 and this reciprocation occurs in time to actuate 75 the ejector to discharge the complete hoop. Also mounted upon the shaft 128 is a bell crank lever formed with a central barrel 129 surrounding the shaft 128 and carrying a rearwardly projecting arm 130 and an upwardly projecting arm 131. The upwardly projecting arm 131 is pivotally connected by means of links 132 to the slide 33, the slide being formed with a depending lug 133 with which the links engage by means of a pin 80 85 134.

Mounted upon the shaft 123 is a relatively large cam disk 135, one face of which is formed with an arcuate rib 136, shown in dotted lines in Fig. 5, adapted to engage 90 intermittently with a roller 137 carried by the arm 130. With the cam disk 135 revolving in the direction of the arrow, Fig. 5, it will be obvious that upon an engagement of the rib 136 with the roller 137, the roller 95 will be lifted and the links 132 shifted forward thereby carrying the clamping member 31 against the hoop. The other face of the disk 135 is formed with a cam track 138 which is approximately ellipsoidal in form, 100 one portion of the ellipse extending concentric to the axis of the disk while the inner portion of the cam track is eccentric to the axis of the disk and extends into proximity to the shaft 123.

Mounted upon a shaft 139 disposed in a slot 140 in the lower ends of the rear legs is an upwardly and rearwardly projecting lever 26 which carries a roller 141 which engages in the cam track 138. The upper end 110 of the lever 26 has a slotted head 142 through which the pin 25 passes, this pin being connected to the slide 18 as previously described.

In order to support the hoop blanks in 115 such position that they may be readily deposited by the operator, between the clamping jaw 31 and the rear portion of the form, we provide a blank supporting frame as illustrated in Fig. 1 comprising upwardly 120 and outwardly projecting supporting brackets 143 and transverse supporting strips 144 connected by longitudinally extending supporting members 145. The width of the frame is, of course, less than that of the 125 shortest hoop which is to be used with the machine. Preferably the frame is also provided at one end with a centering plate des-

gnated 146. This plate is slightly bowed as shown in Fig. 4 so that the outer end of the plate extends laterally beyond the line of the adjacent longitudinal member 145, 5 the inner end of the plate being so disposed from the axial plane of the machine that it will accurately center a hoop as illustrated in Fig. 4.

The operation of the machine is as follows: As soon as a hoop blank is deposited between the clamping jaw 31 and the rear end of the form, the clamping jaw moves forward so as to clamp the middle of the hoop blank in place, and this action tends 10 to bend the hoop blank at its middle so that the ends of the forming arms 20 may easily engage the same. As these forming arms move forward and inward following the cam tracks on the form sections, they press 15 the free ends of the hoop together until the hoop is in the position shown in Fig. 7. It is to be understood that Fig. 7 does not show the complete movement of the arms 20. The complete movement of the arms 20 20 carries the rollers on the extremities of the arms into a position of alignment with the adjacent ends of the sections 5 and 6. Previous to this having happened, a splice plate has been discharged from the magazine 25 and rests upon the support 84 as illustrated in Fig. 8. As soon as the hoop is in position, the bar 67 moves forward into the position shown in Fig. 9 and against the hoop. During the entire time that the 30 hoop is being formed from the blank, the hammer 85 is at the forward limit of its movement so as to form a firm abutment for the meeting ends of the hoop to permit the head of the bar 67 to forcibly press the 35 prongs of the splice plate into the wood of the hoop. As soon as the bar 67 has moved forward and pressed the splice plate into position the cam 111 shifts the slide 71 forward, thus turning the jaws to the position 40 shown in Fig. 9, and bending the splice plate over the hoop and clamping it in place, the hammer having been momentarily retracted to permit this operation. The jaws then open partly as previously 45 described, that is, take the position shown in Fig. 10, and as soon as this has occurred the hammer again moves against the inner face of the splice plate so that the splice plate is compressed against the hoop and between 50 the hammer 85 and the head of the bar 67. As soon as this has occurred, the bar 67 moves away and the jaws are opened, and at the end of the stroke these jaws will take the position shown in Fig. 8, the guides 79 55 extending vertically and being disposed beneath the discharge opening 47 of the magazine. As the jaws move rearward, the rear rounded end of the upper jaw will come in contact with the roller 66 on the

rear end of the bell crank 65 and will shift 65 this roller upward, thus lowering the forward end of the bell crank and depressing the cross bar 60, the rods 57 and the cross bar 59. This action as previously explained will carry the wedge block 62 downward, 70 forcing rearward the lugs 53 and forcing the gate or detent 48 rearward. As the cross bar 59 is depressed, the blade 64 enters between the first splice plate of the series and the next adjacent plate, separates the two and while forcing the first splice plate forward into position to drop through the slot 47, holds the remainder of the splice plates from any forward movement. Upon the next forward movement 80 of the bar 67, together with the jaws 73, the forward end of the bell crank lever 65 will be carried upward by means of the spring 61 on the rods 57 and this will raise the blade 64, permitting the follower 38 to shift 85 the series of splice plates forward so that another splice plate will lie against the gate 48 and into position to drop when the gate moves forward. Meanwhile the hammer has moved backward as has also the clamp 90 31, and as soon as this occurs the forward end of the ejecting lever is depressed, lifting the rear end of the hoop upward into such position that it may be readily grasped by the operator and removed from the machine. It is sometimes necessary to prevent the discharge of the splice plates either because it is desired to stop the operation of the machine in this regard, or else because a portion of the machine breaks, and for this 95 purpose we provide a small shaft 147 which extends through the rear end of the yoke and at its forward end is connected to the middle of the projecting plate or block 49, this plate being slidable to a limited extent 100 with relation to the gate 48 though moving therewith. The forward end of the shaft 105 147 is swiveled to the plate 49 and surrounding the shaft is a coil spring 148 which acts to hold the plate retracted with relation to 110 the gate so that it will move with the gate. Extending across the shaft is a pin 149 contacting with the rear end wall of the yoke, and the yoke is provided with a vertical 115 groove 150 within which the pin is normally received. When it is desired to prevent the discharge of splice plates from the magazine, this shaft 147 is shifted inward against the force of the spring 148 and rotated through a quarter revolution so that the pin 120 149 bears against the inner face of the yoke wall and thus holds the plate 49 slightly projected relative to the gate. When so projected, it will be obvious that the splice plates will not be allowed to move forward 125 so as to drop through the discharge opening, and that as a consequence the blade 64 when it reciprocates will simply enter be-

tween the gate and the first splice plate and will have no effect in the way of feeding the splice plates forward.

What we claim is:

- 5 1. In a hoop forming machine, a supporting frame, a hoop form comprising opposed sections spaced from each other, the forward ends of the sections being pivoted and the rear ends of the sections being adjustable toward or from each other, hoop forming members moving along the faces of said sections and around the form and adapted to engage with the hoop to thereby force the hoop into conformity with the 10 form and cause the ends of the hoop to meet opposite the forward end of the space between said sections, means for bending a splice-plate around the meeting ends of the hoop, and a hammer reciprocatingly mounted in the space between the forward ends of said form sections and acting to clench the splice-plate upon the hoop.
- 15 2. In a hoop forming machine, a form comprising opposed segmental sections spaced from each other, the forward ends of the sections being pivoted and the rear ends being adjustable toward or from each other, each section having a circumferential track and a tangential extension of the track merging thereinto, a slide movable toward or from the form, hoop forming arms pivoted upon said slide, the extremities of the arms being provided with means for engaging the tracks.
- 20 3. In a hoop forming and splicing machine, the combination of a stationary hoop form composed of opposed spaced sections pivoted at their forward ends and adjustable at their rear ends toward and away from each other, a hoop clamping member mounted at the rear end of said form and adapted to initially bend the hoop around the form, said hoop clamping member having a length greater than the uttermost 25 width to which the rear ends of the sections can be adjusted from each other, mechanism for bending the end portions of the hoop blank equally about said form to cause the ends to meet opposite the space between the front portions of the sections, means for applying a splice plate to the meeting ends of the hoop, a mechanism for bending the splice plate around the meeting ends of the hoop, a hammer for delivering a blow upon 30 the splice plate to clamp the ends thereof, said hammer operating in the space between the forward ends of the form section, and means operating in the space between the rear ends of the sections for ejecting the completed hoop.
- 35 4. In a hoop forming machine, a form comprising opposed segmental sections spaced from each other, the forward ends of the sections being pivoted, the rear ends being adjustable toward or from each other,

each section having a circumferential track and a tangential extension of the track merging thereinto, a clamp having an arcuate clamping member disposed in parallel relation to the form and slidably mounted for movement toward or from the form, said member acting to initially bend a hoop blank and clamp it to the form, and said clamping member having a length greater than the uttermost expansion of the rear ends of the form sections, means operating on each side of the clamp and form for bending the hoop blank around the form, means for successively shifting the clamp toward the form operating said bending means, retracting said bending means and retracting the clamp to release the hoop from its engagement with the form.

5. In a hoop forming machine, a circular form provided with outwardly projecting prongs, said form including a track extending parallel thereto, and hoop bending members movable along said track to force the hoop into contact with the form and into engagement with the prongs.

6. In a hoop forming machine, an approximately circular form, oppositely disposed pivoted arcuate arms, means causing the extremities of the arms to travel parallel to the circumference of the form to bend a hoop blank around the form, and springs mounted on the inside faces of the arms to engage the hoop blank when the arms have traveled through the full extent of their movement in one direction.

7. In a hoop forming machine, a form comprising opposed sections spaced from each other, means for bending the hoop blank around said form, an ejector disposed between the sections at the rear end thereof and including a lever, the rear end of which projects beyond said form and beneath the hoop carried thereon, and means for depressing the other end of the ejector to raise the hoop from the form.

8. In a hoop forming machine, a supporting frame, a plate mounted thereon, a hoop form mounted on said plate, guideways formed upon the under side of the plate at the rear end thereof, a slide mounted in said guideways, an arcuate clamp mounted upon the slide and movable with the slide toward and from the form, and means engaging said clamp for reciprocating the same.

9. In a hoop-forming and splicing machine, the combination with a hoop forming mechanism, of a bar movable longitudinally toward and from the hoop-forming mechanism and having a splice plate engaging head, clamping jaws pivoted adjacent their forward ends to the head adjacent the front face thereof, the pivots of said jaws being oppositely disposed to each other, means for reciprocating the bar, and

means for independently oscillating said jaws.

10. In a hoop and forming splicing machine, the combination with a hoop forming mechanism, of a presser bar movable longitudinally toward and from the forming mechanism and having a splice engaging head formed with a splice receiving recess, opposed clenching jaws pivoted adjacent 5 their forward ends to the head above and below the same, means for supporting a splice plate upon and in front of one of said jaws, means for reciprocating the presser bar toward and from the hoop forming mechanism, 10 means for holding the jaws stationary and in open position while the presser bar is moving forward toward the hoop forming mechanism, means for closing the jaws to clench the splice plate around the 15 hoop, means for opening said jaws, a hammer, means for shifting the hammer against the rear side of the splice plate to clench the same, and means for retracting the hammer, the presser bar and the jaws there- 20 with. 25

11. In a hoop forming and splicing machine, the combination with hoop forming mechanism, of a bar movable longitudinally toward and from the forming mechanism 30 and having a splice plate engaging head, said bar being longitudinally slotted, clenching jaws pivoted intermediate their ends to said head above and below the same and having rearwardly extending prolonged 35 portions, a reciprocating member mounted on the bar, links connecting the prolonged portions of the jaws to said reciprocating member, means for reciprocating the presser bar, and means for independently shifting 40 said reciprocating member.

12. In a machine of the character specified, the combination of a reciprocating presser bar, jaws pivotally mounted on opposite sides of the bar adjacent the forward 45 end thereof and movable therewith, said jaws having rearwardly extending arms, actuating means for said jaws movable with the bar and movable independently longitudinally of the bar, and links connecting 50 the rear ends of the arms to said jaw-actuating means whereby upon a forward movement of the jaw-actuating means the links will be forced outward and the jaws rocked upon their pivots to cause the forward 55 ends to move in arcs of circles toward each other and toward the end of the presser bar.

13. In a hoop forming and splicing machine, the combination with a hoop forming mechanism, of a reciprocating presser bar formed with a recess in its forward end adapted to receive a splice plate, of upper and lower splice clenching jaws pivoted at 60 their forward ends upon said head, the forward faces of said jaws being curved, one

of the jaws being provided with upwardly extending splice plate guides and the other jaw with a splice plate support, said support extending outward from the front curved face of the jaw. 70

14. In a hoop forming and splicing machine, the combination with a hoop forming mechanism, of a longitudinally movable presser bar reciprocatable toward and from the hoop forming mechanism, said bar being longitudinally slotted, jaws pivoted at the forward end of said bar and having rearwardly extending prolongations, slides mounted on said bar for independent longitudinal movement, links connecting said prolongations of the jaws with said slides, a cam reciprocating the presser bar, a cam independently rotatable with relation to the first named cam, and a bell crank, one arm thereof engaging said slides and the other 75 arm engaging said cam. 80

15. In a hoop forming mechanism, a splice plate magazine having a discharge opening at its forward end, means for feeding a plurality of splice plates longitudinally along said magazine, a reciprocating gate for alternately closing and opening said discharge opening to permit the discharge of splice plates, vertically reciprocating members mounted on the magazine 90 for actuating said gate, a bell crank lever pivoted to the magazine, the forward end thereof engaging said reciprocating members, the rear end thereof extending downward, a presser bar longitudinally reciprocatable beneath said magazine, jaws mounted on the forward ends of said presser bar, means mounted on the presser bar for independently oscillating said jaws, the rear end of one of said jaws engaging with the 95 depending arm of the bell crank lever to reciprocate the gate and permit the discharge of a splice plate upon the rearward movement of the jaws. 100

16. In a hoop forming and splicing machine, a splice plate magazine having a discharge opening in its bottom at its forward end, means for feeding a plurality of splice plates along the magazine toward the discharge end thereof, a gate shiftable to intermittently cover and uncover the discharge opening, vertically disposed reciprocating members carried upon said magazine and engaging the said gate to reciprocate the latter, a bell crank lever pivoted to the under side of the magazine and having one arm thereof operatively engaging the reciprocating members and the other arm thereof projecting downward and rearward, a presser bar supported beneath the magazine and supported longitudinally thereof, hoop forming mechanism opposed to said presser bar, means for reciprocating the presser bar toward and from the hoop forming mechanism, jaws mounted upon the forward end of the 110 115 120 125 130

presser bar and having rearwardly extending prolongations, the prolongations of one jaw being adapted to engage the downwardly extending end of the bell crank lever 5 to open said gate and permit the discharge of a splice plate from the magazine, a support mounted on the lower jaw and splice plate guides mounted on the upper jaw and adapted to register with the discharge opening 10 when the presser bar is in its retracted position whereby to guide a splice plate onto the said support and in front of said presser bar, and means for independently reciprocating the presser bar and oscillating said 15 jaws.

17. In a hoop forming and splicing machine, the combination of a hoop form, mechanism for bending a hoop around the form, a hammer movable into a position behind the meeting ends of the hoop, means for applying a splice plate to the meeting ends of the hoop, means for forcing said hammer into position behind the meeting ends of the hoop and for then withdrawing 20 said hammer and simultaneously bending the ends of the splice plate around the meeting ends of the hoop, and means for again forcing said hammer forward against the hoop to clench the bent ends of the splice 25 plate.

18. In a hoop forming machine, a hoop form comprising two opposed separated sections, a hammer reciprocatingly mounted between said sections, means acting to bend a 30 hoop blank around said sections to bring the meeting ends thereof immediately in front of said hammer, means for applying the splice plate to the meeting ends of the hoop blank, a cam operatively engaging said hammer to reciprocate it, and means for bending the ends of the splice plate around the edges 35 of the meeting ends of the hoop while the hammer is reciprocating.

19. In a hoop forming machine, a hoop 40 form, means for bending a hoop blank around the form, means for applying a splice plate to the meeting ends of the hoop blank, means for solidly supporting the meeting 45 ends of the hoop blank while the splice plate is being applied, means for bending the ends 50 of the splice plate around the hoop blank,

and means for delivering a final blow upon the bent ends of the splice plate to clench the same upon the hoop.

20. In a hoop forming and splicing machine, the combination with a hoop supporting means, of a splice plate pressing member having a head formed with a concave recess adapted to receive the splice plate, means for supporting a splice plate immediately in 55 advance of the head, means for advancing the pressing member against the hoop to force the splice plate into said recess and initially bend the plate over the front of the hoop, and means mounted on the forward 60 end of the pressing member and movable toward the center of the splice plate for bending the margins of the splice plate over the edges of the hoop and forcing said margins 65 toward each other and toward the outer face 70 of the hoop to cause the splice plate to snugly embrace the hoop.

21. In a hoop forming and splicing machine, the combination with hoop supporting means, of a splice plate pressing member having a head formed with a concave 75 recess adapted to receive the splice plate, oppositely disposed jaws pivoted respectively above and below the head, the inner faces of said jaws extending outward and 80 toward the axial center of the head, means for supporting a splice plate in advance of the jaws, means for advancing the pressing member against the hoop to force the splice plate past said jaws and into said recess to 85 cause the splice plate to snugly fit the front face of the hoop and initially bend the splice plate around the hoop, and means for rocking said jaws upon their pivots to cause the forward ends of the jaws to move toward 90 each other and toward the hoop to thereby bend the margins of the splice plates around the upper and lower edges of the hoop inwardly against the hoop.

In testimony whereof we affix our signatures in presence of two witnesses.
